**METHOD OF RETARDING DEPOSITION OF COKE
IN PETROLEUM FURNACES**
James B. Allen, Houston, and Douglas K. Layne, Arlington, Tex., assignors to Dow Corning Corporation, Midland, Mich., a corporation of Michigan
No Drawing. Filed July 17, 1961, Ser. No. 124,353
3 Claims. (Cl. 208—48)

One of the continuing problems in the petroleum refining industry is the deposition of coke in furnaces where the petroleum is heated to temperatures above the cracking temperature of that material. This is done in many phases in the refining and preparation of petroleum products.

Usually the furnaces employed for heating the petroleum are tube furnaces in which the petroleum passes through a series of tubes, which tubes are heated to temperatures of 500° to 1000° F. At this temperature the petroleum cracks, but is maintained in liquid form by the high temperature and high pressures employed. The liquid product then passes out of the tube furnace into a second stage where it may be either allowed to solidify as in the case of coke preparation, or it may be burned as in the preparation of carbon black, or the liquid may be put through some other process.

The problem which has heretofore been unsolved has been that in spite of the high temperature and pressure employed in the tube furnaces, there was a deposition of solid carbonaceous material on the walls of the tubes. This deposition continues at a sufficient rate so that it seriously interferes with the flow of petroleum through the furnace. In fact, often the deposition was so rapid that the furnace would have to be shutdown after 30 days operation, or at the most after three months operation in order to clean out the tubes. Most of the time the deposition of the coke was so severe that it was cheaper to merely replace the tubes rather than clean them out.

Furthermore, the deposition of coke in the tube reduces the rate of flow of the petroleum, thereby subjecting it to the extremely high temperatures for longer than the desired time. This tends to increase the rate of deposition of the coke and thereby complicated the problem. In addition, the deposition of coke introduced a hazard due to the weakening of the tube walls.

Applicants have found unexpectedly that this deposition of coke in petroleum furnaces can be prevented, or greatly retarded by mixing with the petroleum prior to introduction into the furnace from .1 to 100 parts per million of a methylpolysiloxane, in fluid form, based upon the weight of the petroleum.

The siloxane can be introduced into the petroleum at any time prior to passage through the furnace. Furthermore, the siloxane can be mixed with the petroleum in any convenient manner. The preferred method is to dilute the siloxane with an inert solvent, such as a hydrocarbon solvent. In general, the preferred concentration is from one part siloxane to 30 parts solvent to one part siloxane per 50 parts solvent. The siloxane is introduced continuously into the petroleum, however, the rate of introduction need not be constant. In other words, during the initial part of an operation one may introduce the siloxane at the rate of 10 parts per million based on the weight of the petroleum while during the latter part of an operation one may reduce the siloxane to 3 parts per million.

2

Any methylsiloxane which is in fluid form can be employed in this invention. The term "in fluid form" means that the siloxane can be either a fluid per se at room temperature or it has been rendered fluid by the introduction of a solvent. The term methylsiloxane includes those polysiloxanes in which all of the hydrocarbon substituents on the silicon are methyl radicals and it also includes those siloxanes in which some of the substituents are methyl radicals, whereas the other substituents are hydrogen, or hydrocarbon radicals such as ethyl, phenyl, β -phenylpropyl, β -phenylethyl, or vinyl.

The physical structure of the siloxane is immaterial so long as it is in fluid form. Thus the viscosity of the siloxane can range from less than one cs. to non-flowing gums. Furthermore, it is immaterial whether the siloxane has terminal organic groups or terminal hydroxyl groups or whether it is linear, cyclic or branched in molecular configuration.

The following examples are illustrative only and should not be construed as limiting the invention which is properly delineated in the appended claims.

Example 1

This example illustrates the utility of the method of this invention to prevent coke buildup in a coking furnace employing petroleum residuum.

The petroleum residuum was passed through a pipe line into a coking furnace where it was heated to a temperature of 900° F. The molten residuum was then passed through a second line into a cooling tank where the coke was allowed to solidify. During operation of the apparatus a dimethylpolysiloxane of 12,500 cs. was introduced into the petroleum residuum prior to passage through the cracking furnace at a rate of 10 parts per million. The siloxane was introduced continuously by dissolving it in kerosene to a concentration of one part of siloxane to 50 parts kerosene and then pumping the solution into the petroleum line at a sufficient rate to give the desired concentration of siloxane in the petroleum residuum.

The furnace operated for 8 months without any shutdown due to the deposition of coke in the tubes. When the apparatus was operated without employing the siloxane the furnace had to be shutdown at least about every three months for the cleaning or replacement of the tubes.

Example 2

Equivalent results are obtained when petroleum is passed through a vaporizer furnace and heated at a temperature of 900° F. and the effluent gases thereafter burned to form carbon black.

Example 3

Equivalent results are obtained when the following siloxanes are employed in the process of Example 1:

100 cs. polydimethylsiloxane fluid
Polydimethylsiloxane gum
Trimethylsiloxy endblocked methyl hydrogen siloxane of 50 cs.
60 Methylmethylethylpolysiloxane fluid and Octamethylcyclotetrasiloxane.

That which is claimed is:

1. A method of extending the furnace life in petroleum furnaces by preventing, or decreasing coke accumulation

in the furnace which comprises mixing with the petroleum prior to heating in the furnace from .1 to 100 parts per million of a polymethylsiloxane in fluid form, based on the weight of the petroleum.

2. The method of claim 1 in which the siloxane is a 5 polydimethylsiloxane.

3. A method of extending the furnace life of petroleum tube furnaces by preventing or decreasing coke accumulation in the furnace which comprises mixing with the petroleum prior to heating in the furnace from .1 to 100 parts per million of a polymethylsiloxane in fluid form, based on the weight of the petroleum.
